[57] CLAIM

The ornamental design for an aquarium air pump, substantially as shown.

DESCRIPTION

FIG. 1 is a perspective view taken from the front and left side of an aquarium air pump, showing our new design;

FIG. 2 is a top plan view thereof;

FIG. 3 is a bottom plan view thereof;

FIG. 4 is a right side elevational view thereof; and

FIG. 5 is a rear elevational view thereof.
